UNITED STATES PATENT OFFICE.

JOHN PRITCHARD WILLIAMS, OF NEW YORK, N. Y., ASSIGNOR TO DUPLEX ELECTRIC COMPANY, A CORPORATION OF DELAWARE.

ELECTRIC BURGLAR-ALARM PROTECTIVE SYSTEM FOR SAFES.

1,181,420.

Specification of Letters Patent.

Patented May 2, 1916.

Application filed May 26, 1914. Serial No. 840,976.

To all whom it may concern:

Be it known that I, JOHN P. WILLIAMS, a citizen of the United States, and resident of New York, in the county and State of New York, have invented certain new and useful Improvements in Electric Burglar-Alarm Protective Systems for Safes, of which the following is a specification.

This invention relates to electric burglar-alarm protective systems for safes or the like, and it has particular relation to an improved protective system located with relation to the area of approach to the safe and adapted to automatically actuate an alarm through electric circuit connections when a person enters within the protected area or tampers therewith.

The object of my present invention is to provide a simple and improved protective system of the character mentioned, which can be economically installed and which will effectively and positively protect a safe against unauthorized approach by any person and also against attack by tampering with the protective means or by drilling or other attempts against the same.

A further object of my invention is to provide an improved system of the character set forth which will possess advantages in point of simplicity, inexpensiveness, convenience, positive operation, effectiveness, and general efficiency.

In the drawings—Figure 1 is a perspective view, partly in section, illustrating the general arrangement and location of my improved protective system with relation to a safe. Fig. 2 is a detail cross-section, on an enlarged scale, taken through the protective floor-plate construction, on the line $x-x$, Fig. 1. Fig. 3 is a detail cross-section, on an enlarged scale, taken on the line $y-y$, Fig. 1, and illustrating the supplementary pivoted-plate means for protecting the door of the safe, the door plate being shown partly elevated from normal position and its operative position being illustrated in dotted lines. Fig. 4 is a detail cross-section, on an enlarged scale, taken on the line $z-z$, Fig. 1, and illustrating the spring contact means which is operated by the protective door plate. Fig. 5 is a diagrammatic view, illustrating the circuit connections between the alarm mechanism and the protective floor plates and hinged protective door plate.

Corresponding parts in all the figures are denoted by the same reference characters.

It will be understood that, while my improved protective system is especially adapted for the protection of safes which are established in fixed position, it is also adapted for the protection of vaults or any other receptacles or compartments for the storage of valuables and which are located so that the area of approach adjacent thereto can be protected by the improved means for preventing an attack upon the safe or the like without actuating an alarm.

The protective means for the area of approach to the safe, as comprised in the system constituting my present invention, comprise floor plates extending over said area in superposed position and separated a suitable distance, said plates being spring controlled and in an electric circuit and having contact means for governing said circuit to actuate an alarm when the upper floor plate is depressed.

The preferred construction of such floor-plate protective means, as herein shown, comprises a base-plate member, 1, supported upon the floor base, 3, and covering an area of approach preferably surrounding the safe, 4, which is stationed in desired position, and also comprises a top-plate member, 2, superposed a suitable distance above the base-plate member 1 and corresponding in area thereto, said members being retained in relatively separated position by sustaining springs, 5, interposed between the same. The base-plate member 1 is constituted by a bottom plate, 6, resting upon the floor base 3, an upper plate, 7, an insulating sheet, 8, of fiber or other suitable material, interposed between the plates 6 and 7, and a top insulating sheet, 9, extending over the plate 7. The top-plate member 2 is constituted by a top plate, 10, forming the top surface of the floor-plate protective means, an under plate, 11, and an insulating sheet, 12, interposed between said plates 10 and 11. The spring means for sustaining the members 1 and 2 in normally-separated position is constituted by bolts, 14, carried by the plate 10 of the top-plate member 2 and projecting downwardly therefrom and through a guide opening, 15, in the insulating top sheet 9 of the base-plate member 2, said bolts carrying a stop nut, 16, at their lower ends, beneath said sheet 9, and surrounded by the 110

coiled springs 5 interposed between the members 1 and 2. The nut 16 operates in a suitable recess, 17, provided in the base construction, and the bolt and nut and spring 5 are out of contact with any of the plates above described except the carrying plate 10. It will be understood that, under the foregoing construction, the springs 5 operate to sustain and support the top-plate member 2 in normal position a suitable distance above and away from contact with the base-plate member 1, the stop nuts 16 limiting the relative normal position of said members 1 and 2, and that the top-plate member 2 is compressible against the action of said springs, to establish contact between the members 1 and 2, when a person enters upon the area of approach to the safe which is protected by the floor-plate means. All 10 of said plates as hereinabove described are electrical conductors and are arranged in an electrical circuit as will be hereinafter set forth, and the contact between the members 1 and 2, for actuation of the alarm 15 when the member 2 is depressed, is constituted, in the preferred construction, by a series of studs, 18, suitably disposed with relation to the area of the top-plate member 2 and projecting downwardly therefrom 20 and insulated from the under plate 11 of the member 2 by blocks, as at 19, of fiber or other suitable material, said studs being adapted to contact with plate-strips, 20, arranged in series upon the top surface of the insulating 25 sheet 9 of the base-plate member 1, to underlie the operative area of the contact studs 18, and in circuit as hereinabove described.

In the preferred construction at the edge opening between the normally-separated members 1 and 2, the surrounding edge portion of the top plate 10 of the member 2 is turned downwardly, as at 21, and carries a curved extension lip, 22, suitably insulated from the under plate 11 by a strip or block, 23, as at 23, of fiber or other adapted material, and the surrounding edge portion of the upper plate 7 of the base-plate 1 is extended up and around and over the top of the top insulating sheet 9, as at 24. At the edge 30 opening between the members 1 and 2, under the construction just described, upon depression of the member 2 the extension lip 22 of the top plate 10 of the member 2 is adapted to contact with the edge-extension 35 24 of the upper plate 7 of the member 1, for the purpose of operating the circuit to actuate the alarm, and the same result would ensue if a metallic instrument were inserted at the edge opening to establish connection 40 between the extensions 22 and 24. To further protect the edge opening against the insertion of a metallic instrument in an attack to damage the floor-plate protective means, the extension lip 22 of the top plate 45 10 of the member 2 is preferably curved or

bowed inwardly, as at 25, and is pliable or compressible, so that pressure upon the same will spring said lip into contact with a metallic strip, 26, carried by the insulating strip 23 and in circuit connection with the 70 under plate 11 of the member 2, whereby, said lip 22 and said plate 11 being of different polarity in the circuit connections as hereinafter described, the circuit will be operated to actuate the alarm. 75

The construction of the members 1 and 2, as hereinbefore described, is such that an attempt to drill through the floor-plate protective means with a metallic instrument would establish connection between the plates 10 and 11 of the member 2 or between the plates 6 and 7 of the member 1, which plates are relatively of opposite polarities in the circuit arrangements as hereinafter set for, and thus operate the circuit to actuate the alarm. 80

In the installation of my improved electric protective system under initial conditions, the floor-plate protective means constituted by the members 1 and 2 is preferably seated in a recess, 27, provided in the floor structure 3, as herein shown, so that the top plate 10 of the member 2 is flush with the normal floor surface; but in conditions of installation with respect to safes 90 and floors positioned under established conditions, the floor-plate protective means may be simply arranged as a mat upon the normal floor surface and extending over the area of approach to the safe, as will be 100 readily understood. The safe itself usually rests upon the floor structure 3 and to accommodate this condition the floor-plate protective means is provided with suitable openings or cut-away portions, as at 28, 105 through which the standards or supports of the safe project. 110

I have herein illustrated one preferred circuit arrangement of the various plates as comprised in the members of the floor-plate protective means, though it will be understood that any suitable arrangement of circuits may be employed, and that the mechanism is adapted to operate on either open or closed circuits or on a combination 115 of both open and closed circuits. The open-circuit arrangement herein shown consists of a positive conductor, 29, extending from the top plate 10 of the member 2 to the positive side of a battery or source of electrical energy, 30, and a negative conductor, 31, extending from the under plate 11 of the member 2 to the coil of an automatic drop, 32, and through the contact, 33, and pivoted drop-arm, 34, and frame, 35, of said drop, 120 to the negative side of the battery 30. In like manner, a positive conductor, 36, extends from the under plate 6 of the member 1, and a negative conductor, 37, extends from the upper plate 7 of the member 1, 125 130

the circuit connection being preferably effected by carrying the positive wire or conductor 36 to a connection with the wire 29, and carrying the negative wire or conductor 37 to a connection with the wire 31. Under the circuit arrangements as just described, if contact is established between the plates 10 and 11 of the member 2 or between the plates 6 and 7 of the member 1, by drilling or similar attack, or between the extension lip 22 of the plate 10 of the member 2 and the edge-extension 24 of the plate 7 of the member 1, by depression of the member 2, the circuit through the battery 30 will be closed. In said circuit arrangements, it will be noted that the contact studs 18 carried by the top plate 10 of the member 2 are in circuit with the positive side of the battery through said plate 10, and that the contact strips 20 carried by the insulating sheet 9 of the member 1 are in circuit with the negative side of the battery through a wire or conductor, 38, extending to a connection with the wire 37, and that therefore the depression of the member 2 to bring the studs 18 in contact with the strips 20 will close the circuit. The closing of the circuit, through any of the operative actions as just above described, will energize the magnet of the automatic drop 32 and cause the action of the armature thereof to release the pivoted arm 34 of the drop from the contact 33 and to a contact, 39, thus opening the circuit through the drop and closing a branch alarm circuit to actuate the alarm continuously until the automatic drop is re-set. Said normally-open branch alarm circuit, when thus closed, extends as follows: from the positive side of the battery 30 through the wire 29 and through a conductor or wire, 40, in connection therewith and extending to a magneto bell device or other alarm means, as at 41, and through said alarm device and a conductor or wire, 42, extending to the contact 39, and from thence through the drop-arm 34 and frame 35 of the automatic drop 32, and the wire 31 to the negative side of the battery 30. The wires of the normally-open circuit, which extend between the plate conductors of the members of the floor-plate protective means and the battery and automatic drop, are preferably carried in a cable, under suitably insulated conditions, and housed in protecting tubes, 43, which may extend, under some preferred circumstances of installation, through the walls, as illustrated at 44 in Fig. 1, of the room or compartment within which the safe is located. Said cables are extended or carried to any suitable point at which it is desired to locate the alarm; for instance, to an adjoining room or compartment or to a central station. The circuit batteries and automatic drop and branch alarm circuit, as above described, are preferably located at the alarm station and inclosed within a suitable box or casing or other protective means, as illustrated at 45. The general arrangement of the circuit wires as above indicated protects them against cutting or similar attack to destroy the operative circuit conditions.

At a convenient or desired point in the circuit connections between the floor-plate protective means and the alarm means, a switch is interposed in the circuit, whereby the circuit may be controlled to retain it open against operative conditions during periods when it is desired to permit usual access to the safe without actuating the alarm, and to throw the circuit into operative status during periods when it is desired to protect the safe against unauthorized approach or access thereto without actuating the alarm. The controlling switch, indicated at 46, may be of any usual or adapted construction, but I preferably employ a "lock-switch" of any well-known type adapted to be operated by a key to bring its contacts into and out of circuit, so that its operation is governed by a key in possession of an authorized person and it is thus protected against unauthorized operation to cut out the protective circuit.

In the improved floor-plate protective means, as comprised in my invention and improvements, I also provide a supplementary means for protecting the door of the safe or other receptacle for the storage of valuables against unauthorized opening, said door protective means comprising a hinged door-plate member, 47, adapted to be elevated to position extending in front of and across the door and operating upon circuit connections to cause the actuation of the alarm if it is moved or returned to normal position or tampered with by drilling or similar conditions of attack. In the preferred construction of said door-plate protective means, the top member 2 of the floor-plate protective means is provided with a depression, 48, corresponding to the area of the door-plate member 47 and located immediately in front of the protected safe. At said depression, the plate construction forming the bottom or base portion thereof is substantially the same as the plate construction constituting the other portions of the top member 2 of the floor-plate protective means, and the door-plate member 47 is adapted to normally fit in said depression with its top surface flush with the top surface of said member 2. The hinge connection of the door-plate member 47 with the floor-plate member 2 is constituted by an extension of said member 2, as at 49, immediately in rear of the depression 48 and projecting over a supplementary deeper depres-

sion, 50, in the member 2, which depression 50 is located at the rear edge of the depression 48. Said extension 49 corresponds in its plate construction to the main portion of the member 2, and is connected to said main portion by a joint, as at 51, formed by downwardly-extending flanges, 52, at the meeting edges of the top-plate sections 10 of the member 2, which flanges are bolted together, as at 53. The front edge of the top plate 10 of the extension 49 forms the hinge, as at 54, upon which the door-plate member 47 is mounted. Said member 47 is substantially the same in plate construction as the top-plate member 2, and is constituted by a top plate, 55 (corresponding to the plate 10), which is connected to the hinge 54, and an under plate, 56 (corresponding to the plate 11), said plates being separated by an interposed insulating sheet, 57 (corresponding to the sheet 12), and said member 47 has additionally a bottom plate, 58, which is separated from the plate 56 by an insulating sheet, 59. Said bottom plate 58 is extended to connection with said top plate 55, as at 60, and is of the same positive polarity therewith in circuit. The under or intermediate plate 56 has an extension, 61, at its rear edge, which contacts, as at 62, at all times during the normal or hinge action of the door-plate member 47, with an extension, 63, of the under plate 11 of the extension hinge-portion 49 of the top-plate member 2. Said extension 63 follows a segmental course at the bottom of the supplementary depression 50, to conform to the arc movement of the rear-edge extension 61 of the plate 56 when the door-plate member 47 is moved upon its hinge, and said extension 63 has a free projective position to enable a spring action whereby the contact 62 will be effectively maintained during the movement of the door-plate member 47. Under the circumstances just described, the under or intermediate plate 56 of the member 47 being at all times in contact with the extension 63 of the plate 11, said plates 56 and 11 are of corresponding negative polarity in circuit. Thus, an attempt to drill through the door-plate member 47, when in operative position, with a metallic instrument, will establish circuit connection between the plates 55 and 56 or the plates 58 and 56, and cause the actuation of the alarm through the circuit connections hereinbefore described.

The door-plate member 47 has its circuit connections, in the preferred and relative arrangement, through the plates of the floor-plate protective means, as above described, and it is operative to govern the conditions of the alarm circuit, to cause the actuation of the alarm, by action upon circuit contacts arranged with relation to the movement of said member 47. In the preferred construction for this purpose, a contact con-

stituted by a stud, as at 64, is carried by and in connection with the under plate 11 of the top-plate member 2, at a suitable point beneath the depression 48, which stud is adapted to be engaged by the contact end, 65, of a spring-controlled bolt, 66, slidably mounted in the space between the members 2 and 1 and projecting through and in contact with the top plate 10 of the member 2 into the supplementary depression 50 at the front wall thereof, as shown at 67. Said contact bolt 66 has its slidable bearing in a block, 68, of fiber or other suitable insulating material, whereby the bolt is insulated from the plate 11, and said block also forms the socket for the coiled spring, 69, which governs the action of the bolt. Thus, the contact stud 64 and the bolt 66 are of opposite polarity in circuit, and the circuit is open at said contact means when the bolt is held in position against the action of its controlling spring 69. This position of the bolt is maintained by action of the door-plate member 47, when the latter is in upright operative position for the protection of the door of the safe, 90 by means of an extension, 70, at the rear edge of the member 47, which extension is constituted by an extension of the insulating sheet 59 between the plates 58 and 56 and an extension of said bottom plate 58. 95 Said extension 70 moves in the supplementary depression 50, in the hinge action of the member 47, and when the latter is raised to vertical position the extension bears upon the end 67 of the bolt 66 and moves and retains the latter from contact with the contact stud 64. Thus, the alarm circuit is maintained in open condition when the door-plate member 47 is in operative position, and is adapted to operate upon any attack upon the system which closes the circuit as hereinbefore described, and if the door-plate member 47 is tampered with in an attempt to move it upon its hinge from its upright operative protective position, the 100 pressure upon the bolt 66 is released and its spring control returns it immediately to normal position with its contact end 65 in contact with the stud 64, which closes the circuit and causes the actuation of the alarm. 115

From the foregoing description, it will be understood that any attempt to move the door-plate member 47 from its upright operative position, by the employment of a rod or instrument operated at some distance 120 from the safe and without entering upon the protected area of approach thereto, will cause the closing of the protective alarm circuit and the consequent actuation of the alarm, independent of any action of the 125 floor-plate protective means or any attack upon the latter. Under some circumstances of installation, the contact stud 64 and the bolt 66 may be insulated from their respective plates 11 and 10 by which they are 130

in circuit through the plates of the floor-plate protective means, and may be arranged in an independent circuit consisting of wires or conductors extending respectively from 5 said stud 64 and bolt 66 to the alarm means and controlled by its own switch, whereby the movement of the door-plate protective member 47 will be independent of any circuit connections with the floor-plate protective means and will not affect the circuit 10 conditions of the latter, as will be readily understood. Under the circumstances just stated, the floor-plate protective means will be at all times in operative open-circuit connection whether the door-plate member 47 15 is in up or down position, and the controlling switch of the independent circuit for the contact stud 64 and bolt 66 can be operated to hold said circuit open when the door-plate is down and to close the circuit at said 20 switch when the door-plate is up in operative position and the circuit is open at the contact 64—65.

It will be understood that the construction 25 and arrangement of the hinged door-plate member herein described and claimed as related to the door of the safe, may be arranged with relation to the sides or back of the safe, or a plurality of such members may 30 be arranged with relation to both the door and sides or back, the operative action being the same under all such conditions of positional relation or arrangement.

The operation and advantages of my improved protective system will be readily understood by those skilled in the art to which it appertains. At night, or whenever it is desired to establish a protected period for the safe, under the circuit conditions of 40 the system as herein shown and described, the door-plate member 47 is elevated to its upright operative position across the closed door of the safe, thus opening the circuit contact 64—65, and the circuit to the alarm means is then closed at the lock switch 46 by an authorized person having the key thereto. The alarm circuit to the automatic drop 32 is then open at all the operative contact points of the system and will be 45 closed, to cause the actuation of the alarm, in case of any attack by the approach of a person upon the floor-plate protective means, causing a depression of the top member 2 thereof, or by moving the door-plate member 47 from its upright position, or by an attempt to drill through the floor-plate protective means or the door-plate or to insert an instrument in the edge opening 50 between the members 1 and 2 or otherwise 55 tamper with the protective elements of the system. When it is desired to establish a period during which access to the safe is to be permitted without actuating the alarm, in the morning or at any other desired time, 60 the lock switch 46 is first operated to open 65

the protective circuit to the automatic drop 32 and approach to the safe upon the floor-plate protective means is then permitted, without actuation of the alarm, and the door-plate member 47 can be turned down 70 to its normal position within the depression 48, the release of the bolt 66 to contact with the stud 64 being then permitted without actuation of the alarm. In the conditions just stated, the entire circuit connections to the automatic drop 32 are out of electrical operation, the circuit being open at the switch 46, and free access to and use of the safe is permitted until it is again desired to throw the system into electrically-operative condition for the protection of the safe, by moving the door-plate member 47 to upright position and by operating the lock switch 46 to close the circuit, 75 as above described. 80 85

I do not desire to be understood as limiting myself to the detail construction and arrangement of parts and circuits as herein shown and described, as it is manifest that variations and modifications therein may 90 be resorted to, in the adaptation of my invention to varying conditions of use, without departing from the spirit and scope of my invention and improvements. I therefore reserve the right to all such variations 95 and modifications as properly fall within the scope of my invention and the terms of the following claims.

Having thus described my invention, I claim and desire to secure by Letters Patent: 100

1. An improved electric protective system, comprising a structure to be guarded, a base member extending over the area of approach to the structure to be guarded, a top member constituting the floor surface at the area of approach to the structure to be guarded and arranged above said base member and covering the area thereof, said base and top members each constituting an electrical conductor and being arranged with an intervening space, means for depressibly sustaining said top member, circuit contact means arranged between and in connection with said base and top conductor members and operable upon depression of the top member, and an alarm circuit including the conductors constituted by said base and top members. 105 110 115

2. An improved electric protective system, comprising a structure to be guarded, a base member extending over the area of approach to the structure to be guarded, a top member constituting the floor surface at the area of approach to the structure to be guarded and arranged above said base member and covering the area thereof, said base and top members each constituting an electrical conductor and being arranged with an intervening space, a plurality of conductor layer 120 125 130

plates being comprised in said top member and extending over the area thereof and insulated from each other, means for depressibly sustaining said top member, circuit contact means arranged between and in connection with said base and top conductor members and operable upon depression of the top member, and an alarm circuit including the conductors constituted by said base and top members and the layer plates of the top member, whereby depression of the top member or drilling thereof will cause the actuation of the alarm.

3. An improved electric protective system, comprising a structure to be guarded, a base member extending over the area of approach to the structure to be guarded, a top member constituting the floor surface at the area of approach to the structure to be guarded and arranged above said base member and covering the area thereof, said base and top members each constituting an electrical conductor and being arranged with an intervening space, a plurality of conductor layer plates being comprised in the respective structures of both said top and base members and extending over the respective areas thereof and insulated from each other, means for depressibly sustaining said top member, circuit contact means arranged between and in connection with said base and top conductor members and operable upon depression of the top member, and an alarm circuit including the conductors constituted by said base and top members and the respective sets of layer plates of both said members, whereby depression of the top member or drilling of either of said members will cause the actuation of the alarm.

4. An improved electric protective system, comprising a structure to be guarded, a base member extending over the area of approach to the structure to be guarded, a top member constituting the floor surface at the area of approach to the structure to be guarded and arranged above said base member and covering the area thereof, said base and top members each constituting an electrical conductor and being arranged with an intervening space, means for depressibly sustaining said top member, circuit contact means arranged between and in connection with said base and top conductor members and operable upon depression of the top member, circuit conductors respectively in electrical connection with said base and top conductor members and oppositely disposed with relation to the edge opening between the same, and an alarm circuit including the conductors constituted by said base and top members, whereby either depression of the top member or the insertion of a metallic instrument between the circuit conductors at the edge opening will cause the actuation of the alarm.

5. An improved electric protective system, comprising a structure to be guarded, a base member, a top member constituting the floor surface of the area of approach to the structure to be guarded and arranged above said base member with an intervening space, said top member and base member respectively comprising layer plates insulated from each other, means for depressibly sustaining said top member, circuit contact means arranged between and in connection with said members and operable upon depression of the top member, the layer plates of said respective members being extended in opposite relationship at the edge opening between said members, and an alarm circuit including said base and top members and the layer plates of said members, whereby depression of the top member or drilling of either of said members or the insertion of a metallic instrument between the plate extensions at the edge opening will cause the actuation of the alarm.

6. An improved electric protective system, comprising a structure to be guarded, a base member extending over the area of approach to the structure to be guarded, a top member constituting the floor surface at the area of approach to the structure to be guarded and arranged above said base member and covering the area thereof, said base and top members each constituting an electrical conductor and being arranged with an intervening space, means for depressibly sustaining said top member, circuit conductors respectively in electrical connection with said base and top conductor members and oppositely disposed with relation to the edge opening between the same, and an alarm circuit including the conductors constituted by said base and top members, whereby either the depression of the top member or the insertion of a metallic instrument between the circuit conductors at the edge opening will cause the actuation of the alarm.

7. An improved electric protective system, comprising a structure to be guarded, a base member extending over the area of approach to the structure to be guarded, a top member constituting the floor surface at the area of approach to the structure to be guarded and arranged above said base member and covering the area thereof, said base and top members each constituting an electrical conductor and being arranged with an intervening space, means for depressibly sustaining said top member, circuit contact means arranged between and in connection with said base and top conductor members and operable upon depression of the top member, a plurality of conductor layer plates being comprised in one of said members and extending over the area thereof and insulated from each other, an electrical conductor ex-

tension lip in electrical connection with one of said layer plates of the layer-plate conductor member and in projecting position with relation to the edge opening between 5 said members, said lip being pliable or depressible in relation to a contact in electrical connection with another of said layer plates of said layer-plate conductor member, and an alarm circuit including the conductors 10 constituted by said base and top members and also the conductors constituted by said layer plates of the layer-plate conductor member, whereby depression of the top member or pressure upon said extension lip 15 at the edge opening or drilling through the layer-plate member will cause the actuation of the alarm.

8. An improved electric protective system, comprising a structure to be guarded, 20 a base member extending over the area of approach to the structure to be guarded, a top member constituting the floor surface at the area of approach to the structure to be guarded and arranged above said base member and covering the area thereof, said top and base members being arranged with an intervening space, means for depressibly sustaining said top member, a plurality of circuit contact means arranged between said 25 members at points with relation to their protective area of approach to the safe and operatable upon depression of the top member, and an alarm circuit including said circuit contact means.

30 9. An improved electric protective system, comprising a structure to be guarded, a depressible member constituting an electrical conductor and forming the floor surface at the area of approach to the structure to be guarded, a plurality of conductor layer plates being comprised in said depressible member and extending over the area thereof and insulated from each other, circuit contact means concealed by and in 35 connection with said conductor surface member and operatable upon depression thereof, and an alarm circuit including said contact means and also the conductors constituted by 40 said layer of plates of the conductor surface member, whereby either depression of said member or drilling thereof will cause the actuating of the alarm.

45 10. An improved electric protective system, comprising a structure to be guarded, 55 superposed and separated members arranged at and extending over the area of approach to the structure to be guarded and coacting by depressible action of the top member, a plurality of conductor layer plates being comprised in one of said members and extending over the area thereof and insulated from each other, said layer-plate member constituting throughout its area an electrical conductor, circuit contact means 60 concealed between said members and op-

eratable upon depression of the top member, and an alarm circuit including said circuit contact means and also the conductors constituted by said layer plates of said conductor member, whereby either depression 70 of the top member or drilling through the layer-plate member will cause the actuation of the alarm.

11. An improved electric protective system, comprising a structure to be guarded, 75 a member independent of the structure to be guarded and constituting part of the floor area of approach thereto, said member being operatively mounted in connection with the floor base to swing upwardly 80 in relation to the structure to be guarded and form a wall in front thereof and separate therefrom, circuit contact means comprised in the floor base and operatable when said member is swung downwardly to its 85 normal floor surface position, and an alarm circuit including said circuit contact means.

12. An improved electric protective system, comprising a structure to be guarded, a member independent of the structure to be guarded and constituting part of the floor area of approach thereto, said member being operatively mounted in connection with the floor base to swing upwardly in relation to the structure to be guarded and form a wall 95 in front thereof and separate therefrom, a plurality of conductor layer plates being comprised in said floor-surface member and extending over the area thereof and insulated from each other, circuit contact means 100 comprised in the floor base and operatable when said member is swung downwardly to its normal floor surface position, and an alarm circuit including said circuit contact means and also the conductors constituted by 105 said layer plates of the floor-surface member, whereby either movement of said member or drilling thereof will cause the actuation of the alarm.

13. An improved electric protective system, comprising a structure to be guarded, a member constituting the floor surface at the area of approach to the structure to be guarded, a member hinged to said surface member and operatable to extend in upright 115 position in relation to the structure to be guarded and form a wall separate therefrom, circuit contact means arranged with relation to the hinged movement of said protective member and operatable upon movement thereof, said circuit contact means being concealed by said surface member, and an alarm circuit including said circuit contact means.

14. An improved electric protective system, comprising a structure to be guarded, a member constituting the floor surface at the area of approach to the structure to be guarded and embodying layer plates insulated from each other, a member hinged to 120 125

130

said surface member and operatable to extend in upright position in relation to the structure to be guarded and form a wall separate therefrom, said last-named member embodying layer plates insulated from each other and the respective layer plates thereof being in circuit connection with the respective layer plates of said surface member, and an alarm circuit including the layer plates of said surface member, whereby drilling of either of said members will cause the actuation of the alarm.

15. An improved electric protective system, comprising a structure to be guarded, a member constituting the floor surface at the area of approach to the structure to be guarded and embodying layer plates insulated from each other, a member hinged to said surface member and operatable to extend in upright position in relation to the structure to be guarded and form a wall separate therefrom, said last-named member embodying layer plates insulated from each other and the respective layer plates thereof being in circuit connection with the respective layer plates of said surface member, circuit contact means arranged with relation to the hinged movement of said protective member and concealed by said surface member and operatable upon movement of said hinged member from its protective position, and an alarm circuit including said circuit contact means and the layer plates of said surface member, whereby movement of the hinged member or drilling of either of said members will cause the actuation of the alarm.

16. An improved electric protective system, comprising a structure to be guarded, a depressible member constituting the floor surface at the area of approach to the structure to be guarded and embodying layer plates insulated from each other, a member hinged to said surface member and operatable to extend in upright position in relation to the structure to be guarded and form a wall separate therefrom, said last-named member embodying layer plates insulated from each other and the respective layer plates thereof being in circuit connection with the respective layer plates of said surface member, circuit contact means concealed by said surface member and operatable upon depression thereof, circuit contact means arranged with relation to the

hinged movement of said protective member and operatable upon movement thereof, and an alarm circuit including said circuit contact means and the layer plates of said surface member, whereby depression of the surface member or movement of the hinged member or drilling of either of said members will cause the actuation of the alarm.

17. An improved electric protective system, comprising a structure to be guarded, a depressible member constituting the floor surface at the area of approach to the structure to be guarded, circuit contact means concealed by said surface member and operatable upon depression thereof, a member constituting part of the surface area of said depressible member and operatively mounted in connection therewith to swing upwardly in relation to the structure to be guarded and form a wall in front thereof and separate therefrom, circuit contact means operatable when said last-named member is swung downwardly to its normal floor surface position, and an alarm circuit including said contact means of both the de- 75 pressible member and auxiliary swinging member, whereby either depression of said surface member or movement of said auxiliary swinging member will cause the actuation of the alarm.

18. An improved electric protective system, comprising a structure to be guarded, a depressible member constituting the floor surface at the area of approach to the structure to be guarded, and a supplementary member constituting part of the surface area of said depressible member and operatively mounted in connection therewith to swing upwardly in relation to the structure to be guarded and form a wall in front thereof and separate therefrom, circuit contact means operatable upon either depression of said surface member or movement of said supplementary swinging member, and an alarm circuit including said contact means of both the de- 80 pressible member and supplementary swinging member.

In testimony whereof I have signed my name in the presence of the subscribing witnesses.

JOHN PRITCHARD WILLIAMS.
